US00D487060S

(12) **United States Design Patent** (10) Patent No.: **US D487,060 S**
(45) Date of Patent: **** Feb. 24, 2004**

(54) **WIND FORCE TURBINE FOR THE PRODUCTION OF ELECTRICITY**

6,270,308 B1 * 8/2001 Groppel 415/4.3
6,582,291 B2 * 6/2003 Clark 454/19

(75) Inventor: **Michael Ehrenberger,**
Deisslingen-Lauffen (DE)

* cited by examiner

(73) Assignee: **KBE Windpower GmbH, Zimmern (DE)**

Primary Examiner—Lisa Lichtenstein

(74) Attorney, Agent, or Firm—McGlew and Tuttle, P.C.

(**) Term: **14 Years**

CLAIM

(21) Appl. No.: **29/157,884**

The ornamental design for a wind force turbine for the production of electricity, as shown and described.

(22) Filed: **Mar. 26, 2002**

DESCRIPTION

(30) **Foreign Application Priority Data**

Oct. 19, 2001 (DE) 4 01 09 218

(51) LOC (7) Cl. **13-02**

FIG. 2 is a rear view thereof;

(52) U.S. Cl. **D13/115**

FIG. 3 is a right side view thereof;

(58) Field of Search **D13/115; 416/244 B,**

FIG. 4 is left side view thereof;

416/244 A, 201 R, 175, 203; 415/4.3, 4.5,

FIG. 5 is a top view thereof;

908, 220; 290/55

FIG. 6 is a bottom view thereof;

(56) **References Cited**

FIG. 7 is a front perspective view thereof; and,

U.S. PATENT DOCUMENTS

FIG. 8 is a rear perspective view thereof.
